Application March 16, 1940, Serial No. 324,274

8 Claims. (Cl. 300—2)

Our present invention relates to brush making machines, and more particularly to an improved machine for assembling component parts of a brush into a complete unitary structure.

Our present machine is designed to eliminate to as great a degree as possible the manual assembling of the component parts making up a brush, and particularly a brush of the paint type. In carrying out our invention the handles of the brush are stored in a magazine from which they may be removed one by one and the brush end of a brush consisting of the tuft of fibers assembled within one end of a ferrule are also assembled in a magazine and from which the same may be fed one by one. In accord with our invention the feeding mechanisms for the handles and the brush units are arranged to operate in synchronism and therefore to simultaneously remove a handle and a brush unit from the magazines and feed the same into operative relation to each other in a device which is designed to forcibly insert the end of the handle in that end of the ferrule which is not occupied by the tuft of fibers constituting the brush.

A machine embodying our invention contemplates the use of a plurality of stations at each of which is arranged an operating mechanism for performing an essential operation on the brush in process of assembly. The stations may be any number that is desired, the number, however, depending on the number of operations to be performed. In a preferred showing of a machine embodying our invention there are, in addition to the station for assembling the handle and the brush unit, other stations, as a station for applying nails or other fastening means to one side of the brush, a station for printing any desired marking on one side of the brush, a station for turning the brush over through an angle of 180°, a printing mechanism for performing a printing operation on the other side of the brush, a station for applying nails or other fastening means to the other side of the brush, a station at which the brush or tuft unit is combed and formed, and a station in which is utilized mechanism for placing the completed brush in a collecting magazine.

All of the mechanisms at the various stations are operated in synchronism with each other, and associated with these stations is a mechanism for successively moving the brush parts to the various stations. Certain of the mechanisms at each station are independently operable with respect to other mechanisms at other stations, but viewed as a whole all of the stations are op-

erated from a single source of power, and in synchronism with each other. When in full operation therefore all of the operations to which a brush may be subjected in the assembly operations are being performed simultaneously, one such operation on each of the brushes in succession, so that after the machine is placed in operation a complete assembled brush is produced for each cycle of operations of the machine.

5 A feature of our invention is a unitary combined structure for assembling brush elements into a unitary structure and in which a series of operations are successively performed on the brush elements.

10 A further feature of our invention is a unitary combined structure in which a plurality of operations are successively performed on brush elements to produce a unitary brush structure and in which such operations are successively performed by a series of independent instrumentalities.

15 A still further feature of our invention is an improved unitary combined structure for performing a series of operations on brush elements to produce unitary brush structures and in which all of the operations of the series are performed simultaneously, each operation being performed on a separate brush assembly.

20 30 A still further feature of our invention is an improved unitary combined structure in which operations are performed on both sides of a flat or oval brush assembly and in which instrumentalities are provided for rotating the brush assembly through an angle of 180° at some point 35 during the progress of the brush assembly from one operating instrumentality to another.

25 40 A further feature of our invention is a unitary combined structure in which a plurality of working instrumentalities are arranged in series relation, each performing its own operation, and in which the various instrumentalities are operated in synchronism with each other and with a brush assembly propelling mechanism for moving the brush assembly being operated upon from one working instrumentality of the series to another.

30 45 Other features of the invention will appear more clearly as the description of the invention progresses.

50 55 In the accompanying drawings illustrating a preferred embodiment of our invention:

Fig. 1 is a side elevation of a machine, showing the various stations with the mechanism at each station, together with a means for intermittently moving the component parts of a brush

successively into engagement with the mechanism at the stations.

Fig. 2 is a sectional end elevation through the magazines for the handle and brush units, taken on the line 2—2 of Fig. 1.

Fig. 3 is a sectional end elevation taken on the line 3—3 of Fig. 2.

Fig. 4 is a sectional end elevation taken on the line 4—4 of Fig. 2.

Fig. 5 is a sectional plan view taken on the line 5—5 of Fig. 2.

Fig. 6 is a sectional end elevation through the handle and brush unit assembling mechanism taken on the line 6—6 of Fig. 1.

Fig. 7 is a sectional end elevation taken on the line 7—7 of Fig. 6.

Fig. 8 is a sectional plan view taken on the line 8—8 of Fig. 6.

Fig. 9 is a sectional end elevation through the turning mechanism taken on the line 9—9 of Fig. 1.

Fig. 10 is a sectional end elevation taken on the line 10—10 of Fig. 9.

Fig. 11 is a sectional elevation taken on the line 11—11 of Fig. 9.

Fig. 12 is a sectional plan view taken on the line 12—12 of Fig. 9.

Fig. 13 is a sectional elevation through the brush cleaning and forming unit, taken on the line 13—13 of Fig. 1.

Fig. 14 is a sectional end elevation, taken on the line 14—14 of Fig. 1.

Fig. 15 is a sectional end elevation, taken on the line 15—15 of Fig. 14.

Fig. 16 is a schematic layout illustrating the various operations performed on the component parts of the brush at the various stations on the machine illustrated in Figs. 1 to 15.

Fig. 17 is a schematic layout of the various operations to which the component parts of a brush are subjected to produce a modified form of a brush from that shown in Fig. 16.

Fig. 18 is an exploded view, partly in section, of a brush handle and a brush unit illustrating a method of attaching the same and whereby the nailing operations performed on the component parts illustrated in Fig. 16 may be dispensed with, and

Fig. 19 is an assembled view of the component parts of a brush illustrated in Fig. 18.

Referring to the drawings 10 designates in its entirety the framework of a machine composed essentially of end pedestals 11 secured in spaced relation to each other by longitudinal bars 12 located adjacent the lower end thereof, on the top of which pedestals is mounted a platen or table 13. Secured to the top of the platen or table 13 at one side thereof and in alignment with each other are pillow blocks 14, and in these pillow blocks is rotatably mounted a main drive shaft 15. The main drive shaft 15 has attached thereto at one end a pulley 16 and by means of which the drive shaft 15 is rotated in the desired direction from any suitable source of power (not shown).

Adjacent the end of the platen or table 13 nearest the pulley 16, and on the under side of such platen or table are secured a pair of aligned pillow blocks 17, (but one of which is shown) and in these aligned pillow blocks is rotatably mounted a shaft 18 and which, as clearly shown in Fig. 1, is located beneath and extends perpendicular to the main drive shaft 15. Secured to the under face of the platen or table 13 and on the under side thereof adjacent to the end remote

from the pillow block 17 is a pair of pillow blocks 19, these pillow blocks being in alignment with each other. Rotatably mounted in these pillow blocks 19 is a shaft 20 which lies parallel to the shaft 18 above described.

Secured to the shaft 18 and spaced apart from each other are two sprocket wheels 21 (but one of which is shown), and these sprocket wheels are respectively in alignment with similar sprocket wheels 22 secured to the shaft 20. Over the pairs of sprocket wheels 21 and 22 run endless sprocket chains 23, each of which constitutes a conveyor for moving respectively the handles and the brush ends of the brush to be assembled. Secured to the upper face of the platen or table 13 are tracks 24 for guiding the upper reaches of the sprocket chains 23 and for insuring that such upper reach of each sprocket chain runs in a straight line along and above the table 13.

Secured to the sprocket chains 23, at spaced intervals along the length thereof, are fingers 25 and 26 respectively, the fingers 25 being attached to one of the sprocket chains 23 and the fingers 26 being attached to the other sprocket chain. The fingers 25 and 26 are different from each other, the fingers 25 being designed to engage with the handles for the brushes to move the same, while the fingers 26 are designed to engage with the brush end and move the same. Obviously the sprocket chains 23 move in unison in the same direction and at the same speed.

Adjacent the end of the platen or table 13 in proximity to the pillow blocks 19, and on the top of such table, is a bearing standard 28 in which is rotatably mounted a shaft 29. Secured to the shaft 29 is a helical pinion 30 which meshes with and is driven by a helical pinion 31 secured to the main drive shaft 15. Secured to or formed integral with the shaft 29 is a hub 32 provided with a radially extending arm 33 which has formed therein a T-slot 34. Mounted for slidable adjustable engagement in the T-slot 34 is the head 35 of a stud 36, threaded adjacent its outer end to receive a nut 37.

On the stud 36 is arranged a bearing washer 38, and between the bearing washer 38 and the face of the radially extending arm 33 is placed a bearing bushing 39. By means of the nut 37, washer 38 and bushing 39 the stud 36 may be securely held in any desired position of the head 35 with respect to the T-slot 34.

Rotatably mounted on the bushing 39 is one end of a connecting rod 40. The connecting rod 40 has formed at its opposite end a rack 41 which meshes with and oscillates a pinion 42 formed integral with a housing 44. The rack 41 is held in engagement with the pinion 42 by a housing 43 which encloses the end of the connecting rod 40, and is in turn rotatably mounted on the shaft 20.

Formed integral with the pinion 42 and rotatable on the shaft 20 is an annular housing 44 in which is housed a clutch member 45 formed on a hub 46 secured to the shaft 20. A cover plate 47 may be utilized to close the open end of the housing 44. The clutch member 45 is provided with a plurality of angular cut-outs 45a, the larger length of which forms, with the periphery of the interior of the housing 44, a tapered compartment, as clearly shown in Fig. 15. In each of the angular cut-outs 45a is housed a cylindrical clutch member 48.

With the above described construction, and referring to Fig. 15, it will be apparent that a movement of the rack 41 in the direction of the

arrow shown in such figure will result in rotating the housing 44 and consequently the cylindrical clutch members 48 will move to the highest part of the angular cut-outs 45a. Under these conditions no rotary movement will be imparted to the shaft 20. Conversely, when the rack 41 is moved in a direction opposite to that indicated by the arrow in said figure, the rotation of the housing 44 will result in the cylindrical clutch members 48 moving toward the narrowest part of the wedge-shaped chamber formed by the angular cut-outs 45a and the periphery of the interior of the housing 44, to thereby lock the clutch member 45 to the housing 44 and causing a rotary movement of the shaft 20 in the opposite direction to the arrow shown in Fig. 15, or in the direction of the arrow shown in connection with shaft 20 in Fig. 14.

Because of the manner of connection of the crank 33 to the shaft 29 there is imparted an intermittent rotary movement to the shaft 20, which thereby results in imparting an intermittent movement of the upper reach of the sprocket chains 23. The extent of such intermittent movement may be controlled by adjusting the head 35 of the stud 36 in the T-slot 34. The adjustable intermittent movement of the sprocket chains 23 may be thus adjusted to conform with the spacing of the various stations along the length of the table 13.

In order to prevent retrograde rotary movement of the shaft 20, and therefore a retrograde longitudinal movement of the sprocket chains 23 we provide the following instrumentalities. One of the pillow blocks 19 has formed integral therewith a housing 49 in which is formed an annular chamber. In this chamber is rotatably mounted a clutch member 50, similar in construction to the clutch member 45, but having the cut-outs 45a therein oppositely arranged. The clutch member 50 is secured to the shaft 20 in the usual manner. Fitting in the cut-outs 45a of the clutch member 50 are cylindrical clutch members 48. The open end of the clutch housing 49 is closed by an annular cover plate 51.

This mechanism is so arranged that as the rack 41 rotates the shaft 20 in the direction of the arrow shown in connection with such shaft 20 in Fig. 15, the cylindrical clutch members 48 in the housing 50 will be moved to the large end of the cut-outs 45a. Conversely, when the rack 41 is moved in a direction opposite the direction of movement indicated in Fig. 15 the clutch members 48 in the housing 50 will be moved to the smallest end of the cut-outs 45a to thereby lock the clutch member 50 to the housing 49, and thereby prevent retrograde rotary movement of the shaft 20.

Mounted on the table 13 between the upper reaches of the endless sprocket chains 23 is a table or slide 60 over which the handles of the brushes are moved step-by-step by the endless sprocket chains. Also mounted on the table 13 and arranged parallel to the table or slide 60 is a second table or slide 61 over which the brush units of the brushes are moved step-by-step by the endless sprocket chains 23. The tables or slides 60 and 61 extend throughout the whole length of the table 13, and are periodically interrupted wherever such interruption is necessary to provide a space for some mechanism for performing an operation or operations on the brush units. The tables or slides 60 and 61 are of appropriate height above the table 13, though not necessarily of the same height, and such

tables or slides at the exit end thereof curve downwardly as indicated by the reference character 201, so as to assist in guiding the assembled brushes into a receiving device which transfers the completed brushes into a collecting mechanism.

Arranged along the length of the platen or table 13 and spaced apart from each other, and in such a manner as to be adjustable toward 10 and from each other to vary the distance between them, are mechanisms for performing various operations on the component parts of the brushes. Such operations may be assembling the component parts into a unit brush; securing such component parts in position relative to each other; marking the component parts to designate 15 the type and size of brush or any other information that may be desired; turning the component parts of the brush over through any desired angle to bring any other desired portion thereof into operative relation with the assembling mechanism; brushing and treating the fibrous portion of the brush to size the brush, etc.

The above mechanisms are located on what 20 we call stations, and at each station is an operating mechanism, and in the ordinary brush such mechanisms are as follows. An assembling mechanism for assembling the component parts of the brush into a unitary structure. A first

25 marking station where the size of the brush being operated on is marked. A first nailing station where securing means is applied to rigidly hold the component parts of the brush in assembled relation. A first printing station wherein 30 desired indicia is printed on one side of the assembled brushes. A turning mechanism for turning the assembled brush unit over to any desired angle to bring a face thereof into engagement with the succeeding mechanism, by means of 35 which the printing is applied to the other face of the brush. There is then arranged a second nailing station where additional securing means is applied to the nailing station to hold them to the same in more firmly assembled position. 40

45 There is then arranged a brushing station having mechanism for combing, brushing, and cutting, and forming the assemblage of bristles into the desired shape and form. Other mechanisms may be added if the necessity therefor arises.

50 The assembling station is designated at the right-hand side of Fig. 1, and the details of such assembling station are illustrated in Figs. 2, 3, 4 and 5, and referring to such figures, together with Fig. 1, there is shown a brush unit magazine 62 having a plurality of superimposed brush units 63 therein and with the bottommost brush unit 63 resting on the table or slide 61. There is also arranged a handle magazine 64 having a plurality of superimposed handles 65 55 therein, the bottommost handle of which rests on the table or slide 60. The brush units 63 and handles 65 are placed in their respective magazines manually, as is usual.

60 Associated with the magazines 62 and 64 is 65 a mechanism for assembling the brush units 63 and handles 65. This mechanism comprises the following instrumentalities. Beneath the table 13 and secured to the underface thereof, are aligned pillow blocks 66 in which is rotatably mounted a shaft 67. The shaft 67 is arranged parallel to the shaft 18, and, therefore, extends perpendicular to the line of movement of the upper reaches of the endless sprocket chains 23. 70 Secured to the shaft 67 adjacent to the pillow

block 66 beneath the magazine 64 is a cam 88, such cam being provided with a cam race 89.

On top of the table 13 and secured thereto by screws 78 is a slideway 71 provided with a V-shaped groove 72 therein, and which extends longitudinally of the member 71 and parallel to the shaft 67. Secured to the top face of the table 13 are aligned bearings 73 in which is slidably mounted a shaft 74. Secured to the shaft 74 and adjustable thereon is a member 75 having formed integral therewith a V-shaped member 76 which slides in the V-shaped groove 72 of the member 71 and is also provided with an upwardly extending arm 77 provided with an enlargement 78 at the top thereof. The enlargement 78 is bored to receive as a sliding fit a shaft 79, such shaft being secured in adjusted position by the bolt 80. Secured to, or formed integral with one end of the shaft 79, is a V-shaped member 81 which is adapted to engage with the end of a handle 85. Also secured to the member 75 and extending downwardly therefrom is a member 82 provided at its lower end with a cam roller 83 which works in the cam race 89 of the cam 88.

As the shaft 67 is rotated intermittently in the direction of the arrow shown in Fig. 2, it will be apparent that the member 75 will be given a reciprocating motion in the groove 72 thereby giving a reciprocating motion to the member 81. This motion is of sufficient amplitude to move the end of the brush handle 85 from the full line position shown in Fig. 5 to the dot-and-dash line position shown in such figure. This movement is sufficient to insure that the other end of the handle 85 will be seated in the ferrule 84 of the brush unit 63.

Secured to the shaft 67 and spaced apart from each other are the cams 85 and 86. Secured to the table 13 in any desired manner is a member 87 which has secured thereto by pin 88 a shaft 89. One end of such shaft 89 protrudes beyond the limits of the member 87 and has rotatably mounted thereon the levers 91 and 92. The levers 91 and 92 are similar in construction and constitute mechanism for firmly gripping the ferrule 84 of a brush unit 63 against movement during the period when the end of the handle 85 is being forced into the ferrule 84 of the brush unit by the mechanism above described.

The lever 91 is provided on its lower end with a rotatably mounted cam roller 93 which engages with the cam surface of the cam 85. The lower end of the lever 92 has rotatably mounted thereon a cam roller 94 which engages with the cam surface of the cam 86. The lower ends of the levers 91 and 92 are constantly urged toward each other by means of a coil spring 95, such spring also tending to keep the cam rollers 93 and 94 in engagement with their respective cams. The upper end of the lever 91 is provided with a V-shaped jaw 96, and similarly the upper end of the lever 92 is provided with a V-shaped jaw 97. These jaws are adapted to engage with and grip the ferrule 84 of the brush unit 63 and hold the brush unit relatively stationary during the brush and handle assembling operation.

The shaft 67 in its rotating movement has the cams 85 and 86 mounted thereon in such a position as to have the coil spring 95 exert its maximum force on the lower ends of the levers 91 and 92, and thereby have the maximum pressure exerted by the V-shaped jaws 96 and 97 on the ferrule 84 of the brush units 63 during the

period that the cam 88 is operating on the cam roller 83 to move the member 81 from the full line position shown in Fig. 5 to the dot-and-dash position shown in such figure. The member 81 during its movement forces the end of the handle 85 into the ferrule 84 of the brush unit 63. As the shaft 67 rotates, the member 81 will be retracted from its extended position and the V-shaped jaws 96 and 97 will be brought out of engagement with the ferrule 84 of the brush unit 63, and into position where the fingers 25 and 28 on the endless conveyor chains 23 will move the assembled brush units out from the magazines 62 and 64 and toward the first marking station. Immediately the assembled brush has been removed as above described, the next succeeding brush will drop downwardly, the brush unit 63 onto the table or slide 81, and the handle 85 onto the table or slide 80.

The first station beyond the assembling station above described is called the first nailing station, and in Fig. 1 is designated generally by the reference numeral 100. The details of the first nailing mechanism are shown in Figs. 6, 7, and 8, and referring to such figures, there is shown an arm or pedestal 101 secured to the top of the table 13 by bolts 102, said arm being provided with a curved magazine or magazines 103 for holding and positioning in proper order the plurality of staples 104. In alignment with the arm or pedestal 101 and secured to the top of the table 13 is a pedestal 105 provided at the end adjacent the delivery end of the magazine or magazines 103 with a jaw opening 106 and through which the ferrule 84 of the brush unit 63 may be fed transversely of the pedestal 105.

Located within the jaw opening 106 is the table or slide 81. Also, on the lower portion of the jaw opening 106, and beneath the delivery end of the magazine or magazines 103, is an anvil 107. In the upper end of the jaw opening 106 is provided a vertical slide 108 in which is slidably mounted a cross head 109 carrying the staple propelling member or members 110, and which engage with the staples 104 in the magazine or magazines 103, and drive the same into and through the ferrule 84 of the brush units 63, and into the handle 85, thereby firmly attaching the handle 85 to the brush unit 63. On the upper end of the pedestal 105 is a shaft 111 on which is pivotally mounted a lever 112 one end of which is provided with a cam roller 113, adapted to be engaged by the working surface of a cam 114.

This cam 114 is provided with a rather rapid rise 115 for rapidly moving the end of the lever 112 containing the roller 113 upwardly. A coil spring 112a, attached one end to the lever 112 and the other end to the pedestal 105, maintains the cam roller 113 in engagement with the cam 114. The other end of the lever 112 is pivotally attached to one end of a connecting link 116. The other end of the connecting link 116 is pivotally attached to the top of the cross head 109. The cam 114 is secured to the main drive shaft 15, preferably by means of the threaded bolt 117. By means of this connection the cam 114 may be readily disconnected from driving connection with the main drive shaft 15. The form of connection is such that any other form of cam than that shown may be easily and quickly substituted.

The endless sprocket chains 23 in their intermittent movement move the assembled brush unit 63 and handle 85 from the assembling sta-

tion, above described, to the first nailing station described above and illustrated in detail in Figs. 6, 7 and 8, thereby bringing the assembled brush units into operative relation with respect to the mechanism above described.

The nailing operation takes place in the manner just described, and when the staple engaging members 110 have cleared the ferrule 84 of the brush unit 63, the cam roller 113 will be in engagement with the cylindrical portion of the cam 114. The next intermittent step of movement of the endless conveyor chains 23 will, therefore, move the assembled brush unit from the first nailing position, above described, to the first printing station designated in Fig. 1 by the reference numeral 120.

The printing mechanism may be any one of a number of commercial printing units now on the market and, therefore, will not be described except generally. The printing mechanism is driven from the main drive shaft 15 in any suitable manner, as by means of a cam similar to the first nailing mechanism. The printing mechanism constitutes essentially all means for heating a stamp or die, a roll 121 of color coated material, such as paper, a suitable heating element for heating the stamp or die and a movable stamp or die holding structure 122, which structure is moved periodically downward to bring the stamp or die into engagement with the brush handle being operated upon. Preferably, the printing mechanism operates in the well known manner where heat and pressure are applied to a stamp or die, and the heat and pressure are utilized to transfer some of the color from the roll 121 carrying colored material to the handle 65 of the brush being operated on.

Preferably, there are two of the printing stations and, therefore, two of the printing mechanism, it being desired to print indicia on two sides or faces of the brush handle 65. Under these circumstances, therefore, it is desirable and practically necessary to interpose between the printing mechanism a mechanism for turning the brush assembly over, so as to bring the unprinted surface thereof into engagement to be operated on by the second printing mechanism. In Fig. 1, the second printing station is designated by the reference numeral 123, and interposed between the stations 120 and 123 is the turning station designated by the numeral 124.

Assuming, therefore, that the first printing operation has been performed and that the endless sprocket chains 23, in their intermittent movement, have moved the brush assembly, just printed, to the next succeeding operating mechanism—in this instance a turning mechanism—the turning mechanism will take the brush assembly from the tables or slides 60 and 61 and will rotate the same through an angle of 180°, after which the turning mechanism will deposit the brush assembly on the tables or slides 60 and 61 and be in position to operate on the next succeeding brush assembly.

The turning mechanism is illustrated in detail in Figs. 9, 10, 11 and 12, and referring to such figures there is shown at the turning station 124, and below the table 13, the aligned bearings 125 and 126 and in these aligned bearings is rotatably mounted a shaft 127. Secured to the shaft 127 is a gear 128 which meshes with and is driven by a gear 129 mounted on and forming part of the first printing mechanism. Secured to the shaft 127, adjacent the gear 128, is a cam 130.

5 Mounted on the top of the table 13 is a pillow block 131 in which is rotatably mounted a shaft 132. Secured to the shaft 132 and extending downwardly therefrom is a lever 133 provided at its lower end with a cam roller 134 engaging the surface of the cam 130. Also secured to the shaft 132 is an arm 135 provided at its outer end with a table or platform 136 adapted to be brought up through an opening in the table or slide 60 and support the handle 65 of a brush assembly, as clearly shown in Fig. 11.

Secured to the shaft 127 at the end remote from the gear 128 is a gear 140. As may be seen from the end elevation in Fig. 10, this gear 140 is a segmental gear one half of the periphery of the gear being provided with gear teeth 141 while the remaining half of the gear 142 is plain or toothless. The gear 140 is adapted to mesh with and drive a gear 143 which is secured to a shaft 144 rotatably mounted in a bearing 145 secured to the upper surface of the table 13. By reference to Figs. 10 and 11, it will be seen that the gear 143 is divided, about its periphery into four zones, such zones being arranged in pairs and 10 diametrically arranged. For example, diametrically arranged on the gear 143 are the arcuate toothless portion 142 on the gear 140 to thereby permit the gear 143 to rotate to a certain angular space while gear 143 remains stationary. Also, 15 diametrically arranged on the gear 143 are the teeth 147, which teeth are adapted to be engaged by the teeth 141 on the gear 140, and whereby the gear 143 may be rotated to bring the arcuate portions 146 successively into operative relation with the toothless portion 142 of the gear 140. As the gear 140 is continuously rotating it 20 will be apparent that the gear 143 will be intermittently rotated and will make one revolution to two revolutions of the gear 140.

Secured to the shaft 144 at the end remote from the gear 143 is a cylindrical disk-like member 148, provided with aligned bosses 149 diametrically arranged on one face of the same. Rotatably mounted on each of the bosses is a shaft, as the shaft 150. Secured to one end of each of the shafts 150 on one side of the disk 148 is a jaw member 151. Secured to each of the shafts 150 on the other side of the disk-like member 148 is a lever, one of such levers being 25 designated by the reference numeral 152, and the other lever being designated by the reference numeral 153. To one end of the lever 152 is attached, through pin 154, a coil spring 155, the other end of this coil being attached, through pin 156, to the disk-like member 148. The coil spring 155, therefore, as viewed in Fig. 10, tends to rotate the lever 152 in a clockwise direction about the shaft 144. The other end of the lever 152 has rotatably mounted thereon a cam roller 157. Also, this other end of the lever 152 has 30 pivotally attached thereto one end of a connecting rod 158, the other end of this connecting rod being pivotally attached to one end of the pivoted lever 153. The end of the lever 153 remote from the connection thereto of the link 158 has 35 rotatably mounted thereon a cam roller 158, similar in construction to the cam roller 157.

As the shaft 127 rotates, the gear 140 is likewise rotated, that is continuously and, therefore, the gear 143 will be intermittently rotated, with a slight pause between each intermittent rotary movement, this action being possible because of the arcuate portions 146 of the gear 143 and the toothless portion 142 on the gear 140, as above 40 described.

The jaws 151 carried by the shafts 160 will, therefore, be likewise rotated and assuming the position of the parts being that shown in Figs. 10 and 11, it will be apparent that when the shaft 127 rotates so as to bring the teeth 141 of the gear 140 into mesh with the teeth 147 on one of the sectors of the gear 143, that such gear 143 will be rotated through an angle of 180° so as to bring the now lowermost arcuate portion 146 of the gear 140 into the uppermost position and, therefore, vice versa, thereby, to rotate the jaws 151 and any article that may be carried thereby through an angle of 180°.

As the articles being worked on by the present machine are at the present time brushes, particularly brushes of the paint type, and as such brushes are normally flat on two opposite faces and it is desired to perform certain operation on such opposite faces, the jaws 151 are so arranged as to hold such paint brushes to always present the flat faces of the brushes to the working instrumentalities. This rotary movement is controlled by the gears 140 and 143, but has no effect on either opening or closing the jaws 151 to permit the insertion and gripping, for the holding of the brushes therein.

This latter is accomplished in the following manner. On the shaft 127 is secured a gear 159. On the shaft 144 is secured a gear 160 which is similar in pitch and diameter to the gear 159. Interposed between the two gears 159 and 160 and rotatably mounted on a stub shaft 161 is an idler pinion 162. In a bearing block 163, secured to the top of the table 13, is a shaft 164 to which is secured a gear 165. To the hub of the gear 165 is secured a cam 166. As the shaft 127 is continuously rotating the shaft 164 will likewise be continuously rotating, and, therefore, the cam 166 will always be in motion, although not always in action. The train of gears 159, 160, 162 and 165 is so proportioned with respect to the gears 140 and 143 that the cam 166 will be brought in engagement with one or the other of the cam rollers 157 and 158a. In other words, assuming the parts of the device to be in the position shown in Figs. 10 and 11 it will be noted that the gear teeth 141 are about to intermesh with the gear teeth 147 on one segment of the gear 143 and to rotate such gear 143. In this position the jaws 151 are now clamped on the ferrule 84 of a brush unit and hold the brush firmly against movement. The gear 165 is rotating, but the cam rollers 157 and 158a will not be engaged by the cam 166 at this time. The gear 140 rotating, will rotate the gear 143 so as to bring the now uppermost arcuate surface 146 into the lowermost position as the beginning of the toothless portion 142 of the gear 140 comes into play and the gear 143 stops with the lever 153 occupying the position now occupied by the lever 152 and bringing the cam roller 158a thereon into the position now occupied by the cam roller 157 in Fig. 10. When this occurs the cam 166 will have been brought into engagement with the cam roller 158a rotating the lever 153 about its shaft 150, and also, through intermediary of the connecting rod 158, rotating the lever 152 against the force of the spring 155. The resultant rotary movement of the jaws 151 opens the same to permit the removal of the brush assembly positioned therein, and permit the insertion of another brush assembly.

This removal of one brush assembly and the insertion of another brush assembly necessarily takes place while the cam 166 maintains the jaws 70

151 separated from each other or in open position, when the cam 166 rides past the cam roller 157 or 158a, as the case may be, the coil spring 155 rotates the levers 152 and 153 and brings the 5 jaws 151 into their gripping or closed position onto the next succeeding brush assembly.

From the turning mechanism above described the assembled brush is brought into operative position with respect to the second printing mechanism, designated in Fig. 1 by the reference 10 numeral 123. This second printing mechanism is identical in construction and operation to the first printing mechanism 120 heretofore described, and, therefore, will not be described in detail.

15 In the continued intermittent movement of the endless conveyor chains 23, the completed brush assembly, after having been operated upon by the second printing mechanism 123 is moved into operative association with a second nailing mechanism 170. The particular details of the nailing mechanism heretofore described and illustrated in Figs. 6, 7 and 8, and, therefore, a further description thereof is not deemed to be necessary.

25 After leaving the second nailing mechanism 170 the brush assembly is brought into association with a brushing and forming mechanism designated in Fig. 1 generally by the reference numeral 171, and illustrated in detail in Fig. 13. Referring 30 to such Fig. 13 it will be noted that the slideways 68 and 69 are associated therewith and over which slides are moved by the endless conveyor chains 23, the completed brush assembly including the handles 65 and brush element 66.

35 On top of the platen or table 13 is mounted a base 172 provided at its top with a bearing 173 which is rotatably mounted a shaft 174. Secured to the shaft 174 is a pulley 175 which is in alignment with a pulley 176 secured to the main 40 drive shaft 15. Over the pulleys 175 and 176 runs the endless belt 177 and by means of which power is transmitted from the shaft 15 to rotate the shaft 174.

45 Pivottally mounted on the shaft 174 is a hub 178 provided with a downwardly extending arm 179 having a bearing 180 at its lower end. Rotatably mounted in the bearing 180 is a shaft 181. Secured to one end of the shaft 181 is a pulley 182 which is in alignment with a pulley 183 secured to the shaft 174, and over the pulleys 182 and 183 runs an endless belt 184, and by means of which power is delivered from the shaft 174 to rotate the shaft 181. Secured to the shaft 181, on the opposite side of the bearing 180, from the pulley 182, is a circular brush 185 which rotates in the direction of the arrow shown in Fig. 13. Also secured to the hub 178 is a downwardly extending arm 186, on the outer end of which is rotatably mounted a cam roller 187. Secured to the main 50 drive shaft 15 adjacent the pulley 176, and in position to be engaged by the cam roller 187 is a cam 188. The function of the cam 188 and cam roller 187 is to give to the circular brush 182 an oscillating movement about the shaft 174 as a center, to swing the circular brush 182 into and out of operative position with respect to the bristles of the brush element 66, as clearly shown 55 in Fig. 13.

60 In order to provide that the brush assembly composed of the handle 65 and brush unit 66 is held in fixed operative relation to the brush 182 we have provided the following instrumentalities. Adjacent the endless conveyor chain 23 carrying the fingers 25 on top of the platen or table 65 13 is secured a pedestal 189. Mounted in such

pedestal 189 is a shaft 190. Secured to the shaft 190 is a lever, one arm 191 of which is curved and provided at its outer extremity with a clamping jaw 192 which firmly clamps the handle 65 of the assembled brush onto the slide 60. Intermediate the ends of the lever arm 191 is provided a stop 193 which not only engages the end of the handle 65 to prevent rearward movement thereof, but which positions the brush unit 66 in operative relation to the circular brush 182. The other arm 194 of the lever, secured to the shaft 190, has pivotally attached at its free end, one end of a shaft or rod 195. Secured to the other end of the shaft or rod 195 is a forked member 196. The spaced arms 197 of which straddle the main drive shaft 15 so as to permit rotary movement of the main shaft 15, while yet permitting a sliding longitudinal movement of the forked member 196 on such shaft. On the forked member 196 is mounted a stub shaft 198, on which is rotatably mounted a cam roller 199 and this cam roller 199 engages with the cam face of a cam 200, secured to the main drive shaft 15.

The cams 188 and 200 are so formed and so disposed on the main drive shaft 15, and are so related to each other and to the mechanisms operated or controlled thereby, that as the brush assembly formed of the handle 65 and the brush unit 66 are moved into proper position by the fingers 25 and 26, carried by the endless conveyor chains 23, the lever arm 191 is operated to bring the clamping jaw 192 and stop 193 into operative relation to the handle 65, to thereby move the handle to the right as shown in Fig. 3 a sufficient distance to bring the brush unit 66 into operative relation to the circular brush 182 and to clamp the brush assembly in fixed position on the slide 60. After this clamping and positioning operation has taken place, the cam 188, engaging with the cam roller 187 on the 40 arm, rotates the arm 179 about the shaft 174 as a center, and brings the circular brush 185 into operative position with respect to the bristles of the brush unit 66 to thereby brush and condition the same, after which the brush 185 is swung out of the way and into the position now shown in Fig. 13. Immediately thereafter the cam 200 operating in conjunction with cam roller 199, moves the rod or shaft 195 to the right, as shown in Fig. 13, raising the lever arm 191 to thereby free the assembled and cleaned brush and permit the same to be moved onward.

Upon leaving the brushing unit 171 described above, the assembled brush moves along the slides 60 and 61 and downward along the curved portion 201 thereof. From the bottom of the curved portion 201 of the slides 60 and 61, the assembled brushes are collected in a holder or magazine 202, and the transition of such assembled brushes from the curved portion 201 to the magazine 202 is accomplished in the following manner.

Referring back to the second printing mechanism 123, it is noted that this printing mechanism is provided with a main shaft 203. On such shaft is secured a face plate 204 provided with a radially extended crank pin 205. Pivots attached to the crank pin 205 is one end of a connecting rod 206. The other end of the connecting rod 206 is pivotally attached to the lower end of a lever 207 which is pivotally mounted intermediate its ends, on a shaft 208 carried by a bearing member 209, secured to the under face of the platen or table 13. The end of the lever 207, remote from the pivotal connection of the

7 connected rod 206 is provided with a rack or recess 210 into which the brush assembly slides from the curved portion 201 of the slides 60 and 61. The rotation of the main drive shaft 203 of the second printing mechanism 123 by the mechanism above described imparts an oscillating movement to the lever 207, the end of such lever, within which is provided the recess 210, swinging from the full line position shown in Fig. 1, in which it receives the assembled brush, to the dot-and-dash line position shown in Fig. 1, where the finished brush is forced into the collecting magazine 202.

Referring now to Fig. 16, there is shown a plurality of views representing the complete series of operations above described and wherein the handle 65 and the brush assembly comprising the ferrule 84 and bristles 66 are shown in disassembled and assembled position, representing the condition of these elements when the same are in the assembling unit heretofore described with respect to Figs. 2, 3, 4 and 5. After the assembling operation, the brush elements 65, 66 and 84 are as shown in the group designated "Assembling." After the first nailing operation by the mechanism designated generally in Fig. 1 by the reference numeral 100, and illustrated in detail in Figs. 6, 7 and 8, the appearance is that shown at the point designated "First nailing." The first printing operation is sufficiently illustrated by the appropriate character in Fig. 16, and also the turning operation is designated as being a turning operation by the arrow in the appropriate figure, whereas the second printing and second nailing operations are also sufficiently indicated in the appropriate stations. In the cleaning operation, so designated, the circular brush 182 has been shown in connection therewith in order not to confuse the brushing operation with other operations which have taken place.

In Figs. 17, 18 and 19, a different form of brush from that illustrated in Fig. 16 is shown, and in which the ferrule 84 of Fig. 16 has substituted therefor a ferrule 211 formed of any suitable, but preferably of non-metallic material. Further, and as shown in Fig. 18, the end of the handle 65 is shown with a wedge shaped split 212 therein and in which is positioned a wedge 213, preferably of wood, and at any rate of non-metallic material. During the assembling operation, therefore, and with regard to the type of brush illustrated in Figs. 17, 18, and 19, the assembling of the brush units 65 and 66 results in the forcing of the wedge 213 in the wedge shaped cut in the end of the handle 65. The ferrule 211, in this form of brush, has the perforation therethrough undercut as indicated by the reference numeral 214, with the result that the material of the end of the handle 65 is forced outwardly at its ends as shown in Fig. 19 as the wedge 214 is driven into the handle 35. In this type of brush, no fastening or nailing operations take place, and it is possible to either remove the nailing instrumentalities illustrated in Fig. 1, and rearrange all the other instrumentalities, or merely disconnect the nailing instrumentalities shown in Fig. 1 from the operating power so that while the brush units will stop at the nailing stations no nailing will take place.

Whereas this invention has been described pursuant to specific forms thereof, it will be understood and agreed that many changes and modifications may be made without departing from the spirit of the invention.

We claim:

1. In a brush making machine, the combination of a frame, a platform mounted on said frame, a plurality of operating mechanisms at stations arranged at intervals along the length of the platform, a main drive shaft, a plurality of endless conveyor chains parallelly arranged with respect to each other and provided with fingers for engaging complementary brush elements to be moved along the platform from one operating station to the other, and means interposed between the endless conveyor chains, the main drive shaft for intermittently moving the upper reaches of the endless conveyor chains step-by-step to thereby move the said brush elements from one operating station to the other, and means located at the station for moving a brush element carried by one conveyor chain toward its complementary brush element carried by another of said conveyor chains.

2. In an improved brush making machine, the combination of a platform, a plurality of operation stations thereon in spaced relation to each other and extending throughout the length of the platform, endless conveyor chains provided with outwardly extending respectively aligned fingers for engaging complementary brush elements to be worked upon and having the upper reaches thereof lying above and parallel to the platform and associated with the plurality of operation stations, means for moving the upper reaches of the endless conveyor chains intermittently step-by-step along the platform to move the fingers thereon successively into association with the stations to thereby position the brush elements at such stations and for maintaining the endless conveyor chains at rest at each station, and means located at the station for moving a brush element carried by one conveyor chain toward its complementary brush element carried by another of said conveyor chains.

3. In an improved brush making machine, the combination of a platform, a pair of endless conveyor chains having the upper reach thereof lying above and parallel to the platform, outwardly extending fingers arranged along the lengths of the endless conveyor chains, a magazine for holding a plurality of brush elements in superimposed relation and with the brush elements extending transversely of the direction of length of the upper reaches of the endless conveyor chains, a magazine for holding a plurality of brush handles in superimposed relation, said handles being held in alignment with the brush elements and also transversely of the length of the endless conveyor chains, a slideway on which the lowermost brush element and handle in the magazines rest, a source of power, a clamping means operated thereby for gripping the brush element and holding the same against longitudinal movement, a plunger engaging with the end of the brush handle and operable to force the brush handle into the brush element, means for operating the clamping means, the handle inserting means, and the endless conveyor chains in synchronism, whereby the clamping means is operated to clamp the brush element in advance of the movement of the handle moving means and to open after the handle has been inserted in the brush element, and to thereafter move the now combined brush element and handle to permit the next lowermost handle and brush element to drop onto the slideway for the next succeeding operation.

4. In an improved brush making machine, the

combination of a series of operating stations spaced apart from each other, endless conveyor chains associated with and having a reach thereof passing through the stations, instrumentalities at each station for performing operations on brush elements, brush element engaging means spaced along the length of the conveyor chains and adapted to engage with and move complementary brush elements relatively toward one another, means for intermittently moving the conveyor chains step-by-step to move the brush elements from one operating station to the other of the series, and to maintain such brush elements at rest at the operating stations for a predetermined length of time, and means operative upon cessation of movement of the conveyor chains for effecting the actuation of said instrumentalities.

5. In a brush making machine, the combination of a frame, a platform mounted on said frame, a plurality of operating mechanisms arranged at stations arranged at intervals along the length of the platform, a plurality of conveyor chains parallelly arranged with respect to each other, fingers on the conveyor chains for engaging brush elements to be moved from one operating station to the other, and means interposed between the conveyor chains and the main drive shaft for intermittently moving the upper reaches of the conveyor chains step-by-step to thereby move the brush elements along the length of the platform from one station to the other, and adjustable to vary the length of each step-by-step movement of the conveyor chains.

6. In a brush making machine, the combination of a frame, a platform mounted thereon, a pair of endless conveyor chains spaced apart from each other and having the upper reaches thereof lying above and parallel to the platform and extending along the length thereof, outwardly extending projections on the endless conveyor chains, means for intermittently moving the endless conveyor chains in synchronism with each other and with a step-by-step movement, magazines mounted on the framework at one end of the platform and above the upper reach of the endless conveyor chains, said magazines being adapted to hold, each of them, a plurality of like brush elements, the brush elements in one magazine being different from the brush elements in the other magazine, the brush elements in one magazine being separated from the brush elements in the other magazine, means for moving the lowermost brush elements in each of the plurality of elements into assembled relation, and means for intermittently moving the endless conveyor chains to thereby remove the assembled brush elements from out of the magazines.

7. In a brush making machine, the combination of a frame, a platform mounted thereon, a pair of endless conveyor chains having the upper reaches thereof extending lengthwise along the platform and above the same, and said chains being arranged parallel to but spaced apart from each other, a drive shaft, means associated with the endless conveyor chains and driven from the main drive shaft for imparting an intermittent step-by-step movement to the upper reaches of the endless conveyor chains, means for varying the length of the step-by-step movement of the endless conveyor chains at will, a pair of brush element magazines arranged at one end of the upper reach of the endless conveyor chains, a magazine for completed brushes arranged at the other end of the endless conveyor chains, instru-

mentalities arranged for operating on the brush elements arranged along the length of the platform at spaced intervals and constituting means for operating on the brush elements, said instrumentalities including a pair of spaced printing mechanisms and means interposed between the printing mechanisms for turning an assembled brush through an angle of 180°.

8. In a brush making machine, the combination of a frame, a platform thereon, a pair of endless conveyor chains having the upper reaches thereof arranged parallel to each other and lying in a substantially horizontal plane above the top of the platform, a slideway mounted on the platform between the endless conveyor chains and constituting a track on which the brush assembly is moved, means for moving the endless conveyor chains intermittently step-by-step to there-

5 by move the brush assemblies, a turning mechanism comprising a rotatable member, clamping jaws diametrically arranged thereon, means for intermittently rotating said member through an angle of 180° and for maintaining the same at rest after each rotary movement, means for rotating the jaws only during the period of rest of the cylindrical member, and means for moving the endless conveyor chains only during the period of rest of the cylindrical member and while the clamping jaws are in open position, to thereby move a brush assembly from out of engagement with said jaws, and to insert a succeeding brush assembly in position to be clamped by the jaws.

MAX M. LANDECK.
BERNARD SCHNEIDER.
